CONTAINER

James E. Annen, Kalamazoo, Mich., assignor to
 Sutherland Paper Company, Kalamazoo,
 Mich.

Application July 22, 1935, Serial No. 32,489

7 Claims. (Cl. 229—5.5)

The main objects of this invention are:

First, to provide a container in which the body portion at least may be formed of fibrous material such as container board having the advantages of a tight sealing of a screw thread and at the same time one in which the cover may be quickly engaged or released with a slight rotative movement.

Second, to provide a container having these advantages in which the cover has a highly efficient seal and at the same time one in which the parts are economical to produce.

Objects relating to details and economies of my invention will appear from the description to follow. The invention is defined and pointed out in the claims.

A structure which is a preferred embodiment of my invention is illustrated in the accompanying drawing, in which:

Fig. 1 is a side elevation of my container partially in vertical central section.

Fig. 2 is a side elevation of the cover.

Fig. 3 is a fragmentary side elevation of the container body.

Fig. 4 is an enlarged fragmentary view illustrating the initial position of the cover in closing.

Fig. 5 is a fragmentary perspective view showing the relation of the cover and the body as the cover approaches its final seating or completely closed position.

Fig. 6 is a fragmentary view showing the cover in its completely closed position.

Fig. 7 is a perspective view illustrating the grasping of the cover for the final closing operation.

The embodiment of my invention illustrated comprises a cylindrical body 1 of fibrous material having a fiber bottom 2 provided with a downturned flange 3 joined to the body by the 40 upwardly and inwardly turned joint seam 4.

In the embodiment illustrated, the bottom 2 has a reinforce or supplementary bottom 5 having a downturned flange 6 at its edge snapped over or engaged above the bead 7 formed by the seam.

The body has a plurality of spiral threads or ribs 8 pressed therein, these ribs being arranged in overlapping relation and their upper ends merging into the upper portion of the body. In the particular embodiment illustrated, there are 50 three of such spiral ribs or threads and they are of relatively high pitch.

The cover designated generally by the numeral 9 is preferably of metal and has a convex body portion 10 with an upwardly projecting cylindrical flange 11 terminating in an outwardly extending

downwardly facing channel rim 12 adapted to receive and wedgingly expand the upper edge of the body portion, the rim of the cover having an outwardly curved inner portion 13 engaging the edge of the rim of the body and flaring it out as 5 shown at 14 when the cover is completely seated, thus forming a wedging sealing engagement with the cover and the body.

The edge 15 of the cover rim is preferably turned upwardly providing a rounded edge 16 10 which slides over the body, the body however being supported by this edge so that the container is not likely to be split or broken when the cover is forced to closed position and the upper edge of the body is flared outwardly into a sealing engagement with the cover as described.

The cover flange merges with the body portion into an annular curved surface 17 so that the cover is easily slipped into the container. The flange of the cover is provided with a plurality of 20 spiral ribs or threads 18 merging at their lower ends into the curved surface 10, their upper ends however terminating short of the upper edge of the flange or the rim of the flange so that the cover has a continuous annular outwardly flared portion 13 as described. The periphery of the 25 rim is preferably indented as indicated at 19 to facilitate grasping.

In assembling the cover and the body, the cover may be initially engaged with the body with a 30 telescoping movement and it will be found that the threads or ribs will yield sufficiently to permit this, the rounded surface of the cover constituting a guide and facilitating the slipping of the cover over the threads. This longitudinal 35 movement brings the threads of the cover and body into meshing engagement so that a relatively slight rotative movement will completely seat the cover, clamping the rim down upon the edge of the body, and expanding and flaring the 40 top portion of the body outwardly so that a very effective sealing joint results. The rounded lip 16 slips easily over the outside of the container and engages and supports it throughout the circumference thereof at a point adjacent the outwardly flared portion. This engagement effectively prevents the splitting or fracturing of the edge of the container as it is flared outwardly as described. The cover may be released in the same way; that is, a relatively slight rotative movement 45 in the opposite direction permits the withdrawal of the cover with a longitudinal movement relative to the body.

My improved container is economical in its parts, has the advantage of very rapid and effec- 50

tive cover closing and one which may be clamped tightly and at the same time can be quickly and easily released.

I have illustrated and described my improvements in a very practical embodiment. I have not attempted to illustrate or describe certain modifications in structure which I contemplate as it is believed that such modifications will be readily understood by those skilled in the art to 10 which my invention relates.

Having thus described my invention, what I claim as new and desire to secure by Letters Patent, is:

1. A container comprising a cylindrical fibrous body member having a plurality of relatively high pitched overlapping screw threads pressed therein with one end of each thread merging into the upper edge of the body, and a convex cover comprising an upwardly extending cylindrical flange 15 joined with the convexed body portion of the cover with an annular curved surface, the flange terminating in an outwardly extending downwardly facing channeled rim receiving the edge of the body member when the cover is completely seated, the flange also having a plurality of relatively high pitched overlapping threads merging at their 20 lower ends into said curved surface whereby the threads of the cover and body may be engaged with a telescoping movement and the cover rotated to completely seat the same and clamp the rim over the upper edge of the body, said upper edge being expanded by said curved surface to seal the container.

2. A container comprising a cylindrical fibrous body member having a plurality of relatively high pitched overlapping screw threads pressed therein with one end of each thread terminating at the upper edge of the body, and a convex cover comprising an upwardly extending cylindrical flange 35 terminating in an outwardly extending downwardly facing channeled rim receiving the edge of the body member when the cover is completely seated, the flange also having a plurality of relatively high pitched overlapping threads whereby 40 the threads of the cover and body may be engaged with a telescoping movement and the cover rotated to completely seat the same and clamp the rim over the upper edge of the body, whereby said upper edge is expanded outwardly in said rim.

3. A container comprising a cylindrical fibrous body member having a plurality of relatively high pitched overlapping screw threads pressed therein with one end of each thread merging into the upper edge of the body, and a cover comprising an 45 upwardly extending cylindrical flange inwardly curved at the bottom and having a plurality of relatively high pitched overlapping threads merging at their lower ends into the curved surface at the bottom of the flange whereby the threads of the cover may be engaged with an initial purely translational telescoping movement and the cover rotated to completely seat the same, the flange terminating in an outwardly extending downwardly facing channel rim receiving the edge 50 of the body member when the cover is seated, the rim and flange joining with an inwardly curved annular portion acting to expand the upper edge of the body member when it is brought into engagement therewith of the body member when it is brought into en-

gagement therewith in the seating of the cover, the outer edge of the rim portion being turned inwardly to provide a rounded lip in supporting engagement with the body of the container adjacent the outwardly flared portion thereof.

4. A container comprising a cylindrical fibrous body member having a plurality of relatively high pitched overlapping screw threads pressed therein with one end of each thread merging into the upper edge of the body, and a cover comprising an 10 upwardly extending cylindrical flange having a plurality of relatively high pitched overlapping threads, the flange terminating in an outwardly extending downwardly facing channel rim receiving the edge of the body member when the 15 cover is seated, the rim and flange joining with an outwardly flaring annular portion acting to expand the upper edge of the body member when it is brought into engagement therewith in the seating of the cover.

5. A container comprising a cylindrical fibrous body member having a plurality of relatively high pitched overlapping screw threads, and a cover comprising an upwardly extending cylindrical flange having a plurality of relatively high pitched 20 overlapping threads, the flange terminating in an outwardly extending downwardly facing channel rim receiving the edge of the body member when the cover is seated, the rim and flange joining with an inwardly curved annular portion acting to expand the upper edge of the body member when it is brought into engagement therewith in the seating of the cover, the outer edge of the rim portion being turned inwardly to provide a rounded lip in supporting engagement with the body of the 25 container adjacent the outwardly flared portion thereof.

6. A container comprising a cylindrical fibrous body member having a plurality of relatively high pitched overlapping screw threads, and a cover comprising an upwardly extending cylindrical flange having a plurality of relatively high pitched overlapping threads, the flange terminating in an outwardly extending downwardly facing channel rim receiving the edge of the body member when the cover is seated, the rim and flange joining with an outwardly flaring annular portion acting to expand the upper edge of the body member when it is brought into engagement therewith in the seating of the cover, the outer edge of the rim portion being turned inwardly to provide a rounded lip in supporting engagement with the body of the 30 container adjacent the outwardly flared portion thereof.

7. A container comprising a cylindrical fibrous body member having a plurality of relatively high pitched overlapping screw threads, and a cover comprising an upwardly extending cylindrical flange having a plurality of relatively high pitched overlapping threads, the flange terminating in an outwardly extending downwardly facing channel 40 rim receiving the edge of the body member when the cover is seated, the rim and flange joining with an outwardly flaring annular portion acting to expand the upper edge of the body member when it is brought into engagement therewith in the seating of the cover.
